[57] CLAIM

The ornamental design for a storage and display box, as shown and described.

DESCRIPTION

FIG. 1 is a perspective view of a storage and display
box showing my new design;
FIG. 2 is a top plan view thereof;
FIG. 3 is a right side elevational view thereof;
FIG. 4 is a rear elevational view thereof;
FIG. 5 is a left side elevational view thereof;
FIG. 6 is a front elevational view thereof;
FIG. 7 is a bottom plan view thereof; and
FIG. 8 is a perspective view thereof showing a position wherein the closure is in an unfolded position.
